HAND TOOLS FOR SCORING AND BREAKING TILE AND THE LIKE

John V. Fitzgerald, Metuchen, N. J.

Application November 29, 1954, Serial No. 471,747

7 Claims. (Cl. 125—23)

The present invention relates to hand tools and more particularly to hand tools for scoring and breaking tile and the like.

Although tile and glass may be broken along a scored line by pressing the tile or glass along the edge of a table or platform it is desirable that a tool be provided for breaking the tile or glass without having to depend on there being a table or platform conveniently located. It is important, however, that any tool provided for such purpose be simple, safe, and handy for the operator.

Therefore a primary object of this invention is to provide a hand tool for scoring and breaking tile which is simple to manufacture, safe to use, and handy for the operator.

A tool combining both the scoring and the breaking operations lends itself to convenience in that the breaking operation generally follows the scoring operation.

Another object of this invention is to provide a tool which conveniently combines in one device both a cutting or scoring wheel and a tile breaker.

The thickness of glazed ceramic tile of different manufacturers will sometimes vary. It is therefore important that a hand tool for scoring and breaking tile accommodate normal variations in thickness of the tile. It has been proposed heretofore to employ an adjustment on the tool to provide for variations in the thickness of the tile. An adjustable tool is necessarily more complicated than a tool without adjustments. The manufacture of an adjustable tool is more expensive.

Still another object of this invention is to provide a hand tool for scoring and breaking tile which will accommodate normal variations in the thickness of the ceramic tile without the necessity of providing adjustments.

By providing a tool having no moving parts it is possible to manufacture the tool by simple die casting or similar mass production techniques.

According to this invention there is provided a hand tool for scoring and breaking tile and the like consisting of a rigid tool including a scoring wheel and formed to apply downward pressure on both sides of a scoring on the surface of the tile while exerting pressure upward underneath the scoring on the tile. This pressure is easily applied with a simple lever which may be operated by one hand while the tile or glass to be cut or broken is held in the other hand.

Other and incidental objects of the invention will become apparent after a reading of the following specification and an inspection of the accompanying drawing wherein:

Figure 1 illustrates one form of the present invention.

Figure 2 shows a front view of one form of the invention.

Figure 3 shows a side view of the hand tool shown in Figures 1 and 2.

Figure 4 illustrates how the hand tool made in accordance with the teachings of the present invention is employed.

2

cordance with the teachings of the present invention is employed.

In the several figures of the drawing the same numeral will be employed to designate the same part.

5 Turning now in more detail to Figure 1 a rigid C clamp or U-shaped member 11 contains a scoring wheel 13. The plane of the scoring wheel 13 is in the plane of the C clamp 11. The scoring wheel 13 is supported on a shaft 15 which may be inserted into a hole which 10 pierces the body of the C clamp 11.

The body of the C clamp 11 contains a handle 17, a portion of which is knurled to provide a firm grip for the user of the hand tool. The combination of the cutter wheel or scoring wheel 13 and the handle 17 provides a very serviceable instrument for scoring ceramic tile and the like.

20 The C clamp 11 contains three pressure points or points of contact 19, 21, and 23. Pressure points 21 and 23 are spaced symmetrically about the plane of the C clamp and in a line substantially perpendicular to the plane of the C clamp. The pressure points 19, 21, and 23 consist of ridges which are parallel to the plane of the C clamp. Pressure points 21 and 23 may also be considered as extremities of an arch which has its apex 25 at 25. The apex 25 of the arch is also in the plane of the C clamp.

25 Grooves 27 and 29 are located in the surface to limit the length of the ridges which define the pressure points 21 and 23. Likewise a groove 31 defines the ridge which establishes the pressure point 19.

30 The operation of the hand tool is illustrated in Figure 4 wherein a piece of ceramic tile 33 has been scored along a line 35 and inserted in the C clamp with its scored side upward. By holding the tile 33 in the left hand and forcing downward on the handle 17 with the right hand in the position as shown at 37 the pressure points 21 and 23 are brought to bear on the top surface of the tile while the pressure point 19 shown in Figure 1 is brought to bear under the tile at the position of the scoring 35. Sufficient pressure is exerted by the hand 37 to cause the tile to break along the scoring 35.

35 The grooves 27 and 29 are so positioned that during the tile breaking operation the grooves 27 and 29 will fall at the edge 39 of the tile 33. This prevents clipping of the edge of the tile 33 at 39 and allows the pressure point 23 to fall inward from the edge of the tile 33.

40 It will be seen that the thickness of the tile to be scored and broken may vary considerably providing it is thinner than the opening 41 best illustrated in Figure 3.

45 Although the invention has been shown and described as a hand tool for scoring and breaking ceramic tile, the tool is equally applicable for scoring and breaking glass.

50 A hand tool constructed in accordance with the teachings of this invention will accommodate normal variations in the thickness of glazed wall tile as made by different manufacturers. Special adjustments or settings of the tool for each thickness of ceramic tile is not required. The hand tool is suitable for scoring and breaking soft tile and very hard red bodied tile. In view of the fact that no moving parts such as hinges or cams are required for the hand tool it lends itself to manufacture by die casting.

55 Having thus described the invention, what is claimed is:

1. A hand tool for scoring and breaking tile and the like comprising, means for scoring said tile, a rigid C clamp having an opening slightly greater than the thickness of the tile to be broken, a first side of the opening having two tapered grooves to provide lines of contact with the tile, said two grooves symmetrically

spaced on each side of the plane of said C clamp and in a line perpendicular to the plane of said C clamp, said two grooves extending inward from the extremities of an arch whose concave surface is inward with respect to the C clamp, a second side of the opening of the C clamp having a single point of contact with the tile, and means on said C clamp for rotating said C clamp with respect to the tile to be broken in the plane of said C clamp whereby when said C clamp engages a scored tile so that said two points of contact engage the scored tile symmetrically about the scoring and said C clamp is rotated by said rotating means the tile is broken at the location of the scoring on the tile.

2. A hand tool for scoring and breaking tile and the like comprising a rigid C clamp, said C clamp having an opening slightly greater than the thickness of the tile to be broken and adapted to engage the edge of the tile at a point where the tile has a score on one of its surfaces, said C clamp having as a permanently fixed part thereof two points of contact with the tile on the scored side of the tile and one point of contact with the tile on the side opposite to the scored side of the tile and under the scoring, a handle extending from said C clamp and located in the plane of said C clamp and at a substantially 45 degree angle with the plane of said contact points of the C clamp, a tile scoring wheel in said C clamp, the plane of the wheel being in the plane of the C clamp and wherein said C clamp and said handle consists of a single piece casting.

3. The invention as set forth in claim 2 and wherein said handle and said tile scoring wheel extend from opposite arms of said C clamp.

4. A hand tool for scoring and breaking tile and the like comprising a rigid single element C clamp, said C clamp having a tile scoring wheel in the plane of said C clamp, said C clamp also having two pressure points on one side and a single pressure point on its other side, said two pressure points spaced on each side of the plane of said C clamp and in a line perpendicular to the plane of said C clamp, said two points falling in a groove whose base forms a discontinuous straight line, said C clamp having an opening slightly greater than the thickness of the tile to be broken, the two points of said C clamp adapted to straddle the scoring of the tile to be broken and on the same side of the tile as the scoring while the single pressure point is adapted to apply pressure to the opposite side of the tile from the scoring and under the scoring, a handle for said C clamp, said handle extending in the plane of said C clamp and at an angle to the position the tile is adapted to take in said C clamp whereby said C clamp may be rotated in the plane of said C clamp with respect to the location of the tile to be broken.

5. A hand tool for scoring and breaking tile and the like comprising a rigid lever consisting of a single piece casting, means attached to said lever for scoring said tile; said lever having a fulcrum intermediate its ends, said fulcrum having two pressure points on opposite sides of the axis of said lever and in a line perpendicular

to the axis of said lever, said two pressure points being adapted to engage the scored side of said tile on opposite sides of said scoring, the extension of said lever beyond said fulcrum having a third pressure point adapted to engage the side of said tile opposite to said scoring and under said scoring, and means for applying pressure to said lever to apply pressure to said scored tile at said pressure points.

6. A cutter for tile and the like comprising a solid U-shaped member having a first and a second end, the first end of said U-shaped member divided into two arms spaced symmetrically about the normal plane of the U-shaped member, said arms each having a pressure point in a line perpendicular to the plane of said U-shaped member and on the inside of said arms with respect to the U-shaped member, the second end of said U-shaped member having a pressure point internal with respect to said U-shaped member, means for scoring said tile positioned on the outside and at the extremity of the second end of said U-shaped member, and means for rotating said U-shaped member in the plane of said U-shaped member for applying pressure to said tile by said pressure points so that the pressure points of the first end of said U-shaped member straddle the scoring on said tile and the pressure point of the second end of said U-shaped member is under the scoring on said tile and on the surface of the tile opposite to the surface which is scored.

7. A hand tool for breaking scored tile and the like comprising a single piece casting consisting of a rigid C clamp having an opening slightly greater than the thickness of the tile to be broken, a first side of the opening having two points of contact with the tile, said two points symmetrically spaced on each side of the plane of said C clamp and in a line perpendicular to the plane of said C clamp, said two points of contact with the tile being formed by an arch in the first side of the opening wherein the axis of the arch is in the plane of said C clamp, there also being grooves in the first side of the opening running in line and perpendicular to the plane of the C clamp, the base of the grooves forming a discontinuous straight line, a second side of the opening of the C clamp having a single point of contact with the tile permanently fixed with respect to said C clamp, and means on said C clamp for rotating said C clamp with respect to the tile to be broken in the plane of said C clamp whereby when said C clamp engages a scored tile so that said two points of contact engage the scored tile symmetrically about the scoring and said C clamp is rotated by said rotating means the tile is broken at the location of the scoring on the tile.
